UNITED STATES PATENT OFFICE.

HENRY W. NIERMEYER, OF INDIANAPOLIS, INDIANA.

NON-REFILLABLE BOTTLE.

1,164,111.

Specification of Letters Patent. Patented Dec. 14, 1915.

Application filed April 30, 1914. Serial No. 835,491.

To all whom it may concern:

Be it known that I, HENRY W. NIERMEYER, a citizen of the United States, residing at Indianapolis, in the county of Marion and State of Indiana, have invented certain new and useful Improvements in Non-Refillable Bottles, of which the following is a specification.

This invention relates to what are called 10 "non-refillable" bottles and other containers of similar character, and the object is to provide a vessel of this class with a neck attachment or seal so constructed and arranged that when the vessel has been filled and the 15 neck attachment or seal applied the vessel may be emptied of its contents, but cannot be refilled or re-used.

I accomplish the above and other objects hereinafter specified and pointed out in the 20 claims, by means of the mechanism illustrated in the accompanying drawing, in which—

Figure 1 is a central vertical section of a bottle provided with my invention. Fig. 2 25 is a view of the upper part or neck of the same, partly in elevation and partly in central vertical section at right angles to the section in Fig. 1. Fig. 3 is a cross section on the line 3—3 of Figs. 1 and 2, and Fig. 30 4 is a cross section on the line 4—4 of Figs. 1 and 2.

Like characters of reference indicate like parts throughout the several views of the drawing.

35 Referring to the drawing, 5 is a bottle which is provided with a neck 6 in which, near the top thereof, is an annular groove 7.

Assembled within the neck 6 is a hollow 40 stopper or seal 10 having an outside annular groove 11 which registers with the groove 7 in the neck when the stopper is assembled, as shown in Figs. 1 and 2. The two grooves registering in this manner from the seat for an expanding lock-washer 12 which is adapt- 45 ed to be contracted in the groove 11 during the insertion of the stopper in the neck 6 and to expand into the groove 7 in the latter to lock the stopper in the neck upon such occurrence. The stopper 10 is provided near 50 its upper end with a side opening 13 which communicates through its top by a port 14 with the hollow interior of the stopper.

The chamber within the stopper passes 55 around the walls of the outlet 13 in the manner indicated by dotted lines in Fig. 2 so that a free and unobstructed discharge

through the stopper is afforded into the outlet 13 through the port 14 at the top of said opening 13 and also at an appreciable distance from the bottom of said discharge opening 13. This provides a formation which prevents direct access into the stopper and neck of the bottle to prevent tampering with the seal, presently to be described. The discharge opening 13 will be temporarily 60 closed by means of a cork shown by dotted lines 15 in Fig. 1, in the usual manner. The inner end of the stopper is reduced in diameter to receive a packing sleeve of cork or other suitable material 9 to seal the joint below the stopper and neck of the vessel. 65

The seal above referred to between the stopper 10 and its support comprises a ball valve 16 which is seated on the upper end of a sleeve 8, which is inserted within the lower end of the stopper 10 and is cemented in place, in the manner shown. The outward movement of the ball 16 is limited by the transverse member 17 of a cage which has 70 legs 18, here shown as four in number, 75 formed integrally with the member 17. The legs 18 are placed astride of the ball 16 and rest upon the sleeve 8. The member 17 is reduced in diameter to provide the discharge openings 19 between each pair of legs 18 for 80 the discharge of the liquid contents of the bottle. The outward movement of the cage is limited by a shoulder 20 formed within 85 the hollow interior of the stopper. It will be noted that the opening through the lower 90 portion of the stopper makes a turn around the walls of the discharge opening 13 which is for the purpose of making the valve mechanism more difficult of manipulation through the opening 13. 95

The ball valve 16 and its surrounding cage and seat sleeve 8 are assembled in operative position within the stopper 10 before the latter is placed in the neck of the vessel and locked by the expanding lock-washer 12. 100

In the operation of my device the ball valve 16 seats itself automatically in the top of the sleeve 8 when the bottle is held in a normal upright position, or anywhere above a position of the bottle upon its side. This 105 automatic seating of the valve is due to gravity. When it is desired to pour out a portion of the contents of the bottle, the usual tilting of the latter causes the ball 16 to roll away from its seat against the sleeve 110 8 thereby permitting the liquid contents to pass around the ball and around the member

17 and out through the hollow stopper, port 14 and discharge opening 13. But upon any attempt to refill the bottle it is necessary to turn it upside down in order to introduce 5 any liquid at all through the port 14, and before such liquid would pass on into the bottle the latter would have to be righted which would cause the ball valve 16 to become seated and the entrance through sleeve 10 8 to be closed before any liquid could reach the valve or enter the bottle. An effective seal against refilling is thus secured.

While I have described my invention with more or less minuteness as regards details of 15 construction and arrangement and as being embodied in certain precise forms, I do not desire to be limited thereto unduly or any more than is pointed out in the claims. On the contrary, I contemplate all proper 20 changes in form, construction, and arrangement, the omission of immaterial elements, and the substitution of equivalents, as circumstances may suggest or necessity render expedient.

25 I claim:

1. A non-refillable vessel having a neck at 30 its upper end, a hollow stopper in said neck permanently closed at its outer end and having a lateral cork-receiving tube, said tube having a closed end which projects into the stopper and also having cylindrical side

walls and a port communication with the hollow interior of the stopper through the top wall of the tube remote from said closed end of the tube providing an unbroken cork-receiving cylinder between the port and said closed end of the tube. 35

2. A non-refillable vessel having a neck at 40 its upper end, a hollow stopper in said neck permanently closed at its outer end and having a lateral cork-receiving tube, said tube having a closed end which projects into the stopper and also having cylindrical side 45 walls and a port communication with the hollow interior of the stopper through the top wall of the tube remote from said closed end of the tube providing an unbroken cork-receiving cylinder between the port and said closed end of the tube, said stopper having an inner shoulder below said tube, a sleeve 50 permanently secured in the stopper below the shoulder, a cage held between the shoulder and sleeve and a ball-valve in said cage.

In witness whereof, I have hereunto set 55 my hand and seal at Indianapolis, Indiana, this 25th day of April, A. D. one thousand nine hundred and fourteen.

HENRY W. NIERMEYER. [L.S.]
